UNITED STATES PATENT OFFICE.

CYRUS A. McCAIN, OF BENSONHURST, NEW YORK.

PRINTING-PRESS SHEET-DELIVERY MECHANISM.

1,225,669.

Specification of Letters Patent.

Patented May 8, 1917.

Application filed January 8, 1916. Serial No. 71,089.

To all whom it may concern:

Be it known that I, CYRUS A. McCAIN, a citizen of the United States, residing at Bensonhurst, in the county of Kings, State of New York, have invented certain new and useful Improvements in Printing-Press Sheet-Delivery Mechanisms, of which the following is a specification.

The present invention relates to sheet delivery mechanisms for printing presses. Its several features are capable of use in many relations and upon presses of many different types but, as illustrative, I have chosen to embody them in a flat bed cylinder printing press, that is, a press of the type in which a reciprocating type bed cooperates with an impression cylinder. In such flat bed cylinder presses provision is commonly made for giving either a "fly" delivery or a "face-up" or reciprocating delivery. The fly delivery is produced by fly sticks or fingers which engage the under side of the sheet and by rotation about one end convey the sheet with a sweep through the air and deposit it reverse side up upon the piling table, and the latter or reciprocating delivery is brought about by a sheet carrier which engages the under side of the sheet and conveys it longitudinally to a position above the piling table and deposits it thereon printed side up.

The principal objects of the invention are to provide an improved mechanism for carrying and depositing the sheet in the face-up or reciprocating delivery by which sheets of different sizes, weights and thicknesses may be handled with equal facility and efficiency; to provide improved mechanism for gripping the sheet, preferably at its front or forward edge, and holding it as it is being conveyed by the reciprocating delivery mechanism; to provide improved constructions of parts by which the changing over from one style of delivery to the other may be readily accomplished; and to provide an improved arrangement of parts by which the various parts of the delivery mechanism may be raised up and held in elevated position for the purpose of enabling the inking rollers and other parts beneath the delivery mechanism to be properly washed, inspected and removed or replaced.

With these ends in view, my invention consists in certain features of novelty in the construction, combination and arrangement of parts by which the said objects and certain objects hereinafter appearing are attained, all as fully described in the specification, shown in the accompanying drawings, and more particularly pointed out in 60 the appended claims.

In said drawings, Figure 1 is a side elevation of a portion of a two-revolution cylinder printing press equipped with my improved sheet delivery mechanism, the main 55 conveyer, the piling table and other parts being shown elevated so as to give ready access to the parts beneath; Figs. 2 and 3 are plan views of right and left hand portions, respectively, of the delivery mechanism; 70 Fig. 4 is a side elevation of a portion of the delivery mechanism, parts being broken away and other parts shown in section, the plane of section being indicated by the line 4-4 of Fig. 3; Fig. 5 is a detail elevation 75 of a portion of the reciprocating carriage and a supporting way-bar, parts being shown in section taken on a plane indicated by the line 5-5 of Fig. 2; Fig. 6 is a similar view illustrating the parts in a different position 80 and at a different point upon the carriage way-bar, the section in this case being upon a plane indicated by the line 6-6 of Fig. 2; Fig. 7 is a side elevation of the carriage and way-bar, showing the parts in their sheet receiving position in association with the conveyer from which the sheet is received by the carriage; Fig. 8 is a similar elevation of the carriage viewed at its delivery position 85 upon the way-bars; Fig. 9 is a view similar 90 to Fig. 7, showing the carriage as it approaches the receiving position; Fig. 10 is a transverse view with parts in section, illustrating the mechanism for providing a connection between the main conveyer frame 95 and the carriage actuating arms by which the conveyer is held in elevated position, as illustrated in Fig. 1; Fig. 11 is a detail plan view of the spring roller of the carriage mechanism and associated parts of the carriage and way-bars upon which the carriage travels, parts being shown in section taken on a plane indicated by the line 11-11 of Fig. 12; Fig. 12 is a view illustrating a por-

tion of the delivery carriage in section taken on a plane indicated by the line 12—12 of Fig. 9; Fig. 13 is an elevation of a portion of a tape-holding bar; Fig. 14 is a similar view of a tape-holding spring roller; and Fig. 15 is a transverse section of the same taken on a plane indicated by the line 15—15 of Fig. 14. Throughout these views like characters refer to like parts.

- 10 Referring to the drawing in detail and keeping in mind that the parts occupy the dotted line positions of Fig. 1 when they are in operative position, 20 designates the feed table upon which the sheets are piled and 15 from which they are fed to the impression cylinder 21 which is mounted in any suitable manner in the frame 22. When fed to the cylinder the sheet is carried around by it in order to receive the impression and it 20 is then stripped from the cylinder by suitable strippers which guide it upon the conveyer tapes 23 of the main conveyer 24. These tapes convey the sheet to a point directly above the fly fingers 25, or into position to be engaged by the stop fingers 26 25 and gripper fingers 27 of the gripping mechanism of the carriage 28. If the fly delivery mechanism is in operation, the fingers 25 will be rotated about their shaft 29 to carry the sheet with a sweep through the air into position upon the piling table 30 which is shown in Fig. 1 in dotted lines, in its proper operative position, thereby delivering the sheet reverse side up. If the 35 reciprocating or face-up delivery is used, then the carriage 28 is moved along the way-bars 31 to carry the sheet printed side up into position to deposit it upon the piling table 30.
- 40 The impression mechanism, indicated by the link 32 connecting a driven rock arm 33 with an eccentric rock arm 34 mounted to actuate the journal box 35 of the impression cylinder, forms no part of the invention 45 claimed in the present application, but constitutes part of an impression mechanism which I have disclosed and claimed in a companion application Serial No. 70411, filed January 5th, 1916. Obviously any suitable impression mechanism may be employed. Likewise, the gripper and guiding mechanism for the impression cylinder, indicated by the guide fingers 36 and 37 mounted upon the guide frame 38, form no 55 part of the present invention but are set forth and claimed in a companion application Serial No. 71705, filed January 12th, 1916. Any other suitable gripper and guiding mechanism might be equally well employed. Likewise, any suitable strippers, for example such as shown in Miehle Patent No. 610,491, dated Sept. 6, 1898, may be employed.

The main conveyer 24 includes side bars

39 which are pivoted at one end to the guide frame 38 and are secured at their other end each to a bearing plate 140 by any suitable means, such as the bolts 41. The plates 40 are provided with bearings for a transverse tape shaft 42 upon which the tape wheels 43 of the main conveyer 24 are secured. Corresponding tape wheels are positioned upon a shaft 44 extending between the end members of the guide frame 38. The tapes 23 pass over these tape wheels in the usual manner and the shaft 44 is suitably driven in the well-known manner from the impression cylinder 21. The plate 40 is adjustable relative to the side bars 39 in order to provide for the taking up of any slackness in the tapes 23. This adjustment is preferably accomplished by extending the bolts 41 through slotted openings 45 in the plates 40 into threaded engagement with threaded holes in the bars 39, and by further providing an adjusting screw 46 which is threaded through an opening in lug 47 on an extension 48 of the plate 40. These adjusting screws bear against the ends of the corresponding side bars 39. Lock-nuts 49 serve to hold the screws 46 in adjusted position with the requisite tension upon the tapes 23.

In order to support the main conveyer frame 24 in its normal position, the plates 40 are provided with extensions 50 which rest upon adjustable studs 51 which are respectively screwed into threaded openings in bars 52 which extend inward from the delivery frame extensions 53 of the main frame 22. The studs 51 are provided with lock-nuts 54 by which they may be held in adjusted position.

The fly fingers 25 are secured to a fly shaft 29 which is suitably journaled at its opposite ends in the extensions 53 of the main frame. Each finger 25 is provided with a fly stick socket or holder 56 which surrounds the shaft 29 and is held in adjusted position by a set-screw 57. Each socket is provided with a projection 58. The fingers 25 are secured to the upper faces of these projections by any suitable means, such as the screws 59. For convenience of assembly, the shaft 29 is divided into three parts which are connected together by any suitable means, as bolts 60 which extend through overlapping offset portions of the abutting shaft sections. As before pointed out, the fly fingers 25 convey the sheet to the piling table by a sweep of about 180 degrees about the shaft 29. In order to impart a proper oscillatory movement to the shaft for this purpose, the latter is provided with a toothed gear segment 61 which cooperates with a reciprocating rack 62 which forms an extension of the bar 63 which is pivoted to the upper end of an arm 64 which is in turn pivoted to the main frame. The arm

64 carries an anti-friction roller 65 which runs against the peripheral face of a cam 66 mounted on a driving shaft 67. The bar 63 is moved in one direction by the cam and in the opposite direction by a coiled spring 68 which surrounds it and bears at one end against a collar 69 upon the bar 63, and at the other end against a sleeve 70 which is pivoted at 71 to the frame extension 53 and constitutes a housing for holding the rack 62 in engagement with the toothed segment 61. The sleeve 70 is provided with a guard 72 which surrounds the segment 61, in order to prevent injury to the operator. The collar 69 is adjustable upon the bar 63 and may be held in its adjusted position by means of a set-screw 73. The fly delivery fingers and the associated mechanism for actuating them are similar in arrangement and construction to the mechanism for the same purpose disclosed in the aforesaid Miehle patent and are of themselves old and form no part of the present invention except as they may do so in combination with portions of the reciprocating delivery mechanism. Since the fly delivery mechanism is to be thrown out of operative condition when the reciprocating delivery mechanism is in operation, I provide a locking arm 74 pivoted to the main frame and adapted to engage with the roller stud 65 on the pivoted arm 64 to hold the roller out of the line of movement of the surface of the cam 66. When the locking arm is thus latched to the arm 64, the fly fingers 25 lie below the level of the upper or conveying portion of the tapes 23 and by reason of their relative arrangement upon the shaft 29, they extend between the different tapes of the main conveyer. In order that the fly fingers may be moved independently of the toothed segment 61 and the associated rack 62, I mount the segment 61 so as to rotate freely upon the shaft 29 and to the outer end of the shaft secure an arm 75 which is keyed to the shaft so as to rotate with it. This arm carries a sleeve in which is located a spring-pressed pin 76 which is yieldingly forced inward toward the segment 61. The latter is provided with a suitable opening into which the pin 76 may pass to lock the arm 75 and segment 61 together so that the latter will rotate with the shaft. By removing the pin 76 from its hole in the segment 61, the shaft 29 and the connected fly sticks may be readily moved to any desired position, as for example that illustrated in Fig. 1.

The way-bars 31 of the reciprocating delivery mechanism are secured to the delivery frame extensions 53 by any suitable means, such as the bolts 77, and they extend outward in the direction of the piling table 30 and in substantial alinement with the side frames of the press. The carriage which rides upon

these way-bars consists of carriage frames 65 78 and 79 and transverse connecting shafts 80, 81 and 82. The shafts 80 and 81 carry the stop fingers 26 and the co-operating gripper fingers 27, and the shaft 82 carries a spring roller 83. Each carriage frame is 70 provided with two flanged wheels 84 which are suitably journaled upon studs 85 which extend laterally from the frame. These studs 85 are held in their frames by bolts 85^a and are positioned so that the wheels 84 may 75 travel upon the associated way-bar 31. The transverse rod 80 is journaled at its ends in the carriage frames 78 and 79 so as to rotate therein. The rod 81, on the other hand, is journaled at its ends in arms 86 which 80 are fixed to the shaft 82 by one or more set screws 82^a. The latter is provided at its ends with anti-friction rollers 87 which are adapted to engage the under side of strips 88 secured to the inner sides of the way-bars 31. The transverse shaft 82 is journaled at its ends in depending arms 89 of the carriage frames 78 and 79 and held from rotation therein by one or more set-screws 90. A spring 91 surrounds the shaft 90 85 and is arranged to engage the shaft at one end and the surrounding spring roller 83 at the other, so as to yieldingly hold the latter in a given position but to allow it to be wound up and energy thereby stored up 95 in the spring. The anti-friction rollers 87 by engaging the under side of the strips 88 prevent the carriage from leaving the way-bars.

The spring roller 83 is provided with a 100 plurality of tapes 92 which are secured at one end to the exterior of the roller and at the other end to a fixed bar 93 which is located adjacent to the point at which the grippers of the carriage receive the sheet 105 from the main conveyer tapes 23. The bar 93 is provided at its end with holes through which vertical pins 94 are adapted to pass, and set-screws 95 are threaded through 110 threaded openings in the ends of the bar into setting engagement with the pins 94 so as to hold the bar 93 firmly in position. The pins 94 extend upward from projections 96 upon collars 97 which are sleeved upon the shaft 29 and held in position by set-screws 98. As the carriage moves back and forth upon the way-bars 31, the tapes 92 wind on and off of the spring roller. These tapes may be of any suitable fabric or flexible material and may be of any width suited 115 to the dimensions and locations of the co-operating parts.

In order to actuate the stop fingers 26 and the gripper fingers 27, the shafts 80 and 81 of the carriage are respectively provided 120 with crank arms 99 and 100 which are arranged to extend in the directions illustrated and to have their ends connected by a link

101. By reason of the relation of the arms 99 and 100 and the link 101, that rotary movement of the shaft 80 which would tend to lower the stop finger 26, causes a movement of the shaft 81 which will raise the gripper finger 27. In other words, a rotation of shaft 80 in one direction causes a rotation of shaft 81 in the opposite direction. In order to rock the shaft 80 to bring about this 10 approach and separation of the fingers 26 and 27, the shaft 80 is provided with an arm 102 which is pivotally connected at its free end to the reciprocating rod 103, which passes through a guiding aperture in lug 15 104 upon the carriage frame 79, the arm 102 being located upon the shaft 80 at a point adjacent to said frame. A spring 105 is coiled about the rod 103 and abuts at one end against the projection 104 and at the other 20 end against a collar 106 located upon the rod and adjustable thereon to vary the compression of the spring 105. The arm 102 and rod 105 with their associated parts constitute a spring-actuated toggle which tends to hold 25 the shaft either in the position of Fig. 5 or in that of Fig. 6. To provide for adjusting the movement of the fingers 26 and 27 by this toggle mechanism, the hub of the arm 102 which is sleeved upon the shaft 80, is 30 provided with a set-screw 107, by which the position of the arm relative to the shaft may be varied. The stop fingers 26 are also arranged so that they may be adjusted with reference to the shaft 80 and for this purpose each finger is provided with a collar or hub 108 which is sleeved upon the shaft 80 and held in the desired angular position by means of a set-screw 109.

In operation the fingers 26 and 27 of the 40 gripping mechanism are brought into sheet engaging position at one end of the movement of the carriage and thrown out of that position at the other end of the carriage movement. In other words, as sheet 110 is 45 engaged by the gripping mechanism when the carriage is adjacent to the main conveyer 24 and remains in such engagement until the advancing carriage brings the sheet to its final position and then the fingers 26 and 50 27 are opened and remain open until the returning carriage again reaches a position adjacent to the conveyer. In order to bring about these operations of the gripping fingers 26 and 27, and the corresponding actuations of the toggle mechanism, the shaft 80 is provided at that end which is adjacent to the carriage frame 78, with a cam member 110^a having a cam finger 111 and a cam face 111^a and shoulder 112. The cam member 110^a is positioned upon the shaft 80 and held in adjusted position by means of a set-screw 113. The adjacent way-bar 31 is provided with a pin 114 which extends laterally from it into the path of movement of

the cam finger 111 so as to engage it as the 65 carriage moves toward the conveyer, and, by raising it, rock the shaft 80 to bring the gripper fingers 26 and 27 toward each other, the toggle members 102 and 105 serving to bring about this positive action in the way 70 before explained. Since it is not desired to bring these fingers into close engagement until a sheet 110 has been brought against the down-turned end of the finger 26 in the way illustrated in Fig. 7, provision is 75 made for limiting this movement of the fingers toward each other until ample time has been allowed for the delivery of a sheet from the conveyer tapes 23 to the position of the sheet 110 of Fig. 7. This limiting 80 action is brought about by a stop arm or finger 115 secured to shaft 80 and co-operating with a ledge or cam 116 positioned upon the way-bar 31 adjacent to the carriage frame 79. This ledge 116 lies adjacent to 85 the delivery end of the conveyer tapes 23 and extends only a short distance therefrom. While the finger 115 is in engagement with the ledge 116, the gripper fingers 26 and 27 90 occupy the position shown in Fig. 7, and by reason of the greater speed of the tapes 23 compared with the speed of the carriage as it begins its movement away from them, the sheet is carried forward against the down-turned end of the stop fingers 26 and 95 maintained in that position by the tapes until the arm 115 passes from engagement with the ledge 116 and allows the toggle to engage with the sheet, as illustrated in 100 Fig. 6.

When the carriage has advanced the full length of its stroke away from the main conveyer 24, the shoulder 112 of the cam member 110^a is engaged by a spring-pressed 105 latch 117 located upon the adjacent way-bar 31 at a point adjacent to its outer end, as clearly illustrated in Fig. 1. This latch 117 is inclined at one side so as to be depressed by the face 111^a of the cam member 110^a as the latter advances. At the other side the latch is squared so as to engage the shoulder 112 of the cam member 110^a to rock the shaft 80 in a direction to separate the gripper fingers 26 and 27 from each other as 110 soon as the carriage starts upon its return movement. This action frees the sheet 110. The cam member 110^a is provided with an upward projection 118 having upon its upper edge a nub 119 which co-acts with a depression in a leaf-spring 120 which is suitably secured at one end to a bracket 121 upon the carriage frame member 78. The engagement of the nub 119 with the depression in the spring, tends to hold the cam member 110^a in the position illustrated 115 in Fig. 9 during the return movement of the carriage and to hold the cam member in 120 125

substantially the position illustrated in Fig. 8 during the advance movement of the carriage.

It will be observed that as the carriage 5 moves forward, the tapes 92 which are associated with the spring roller 83, will be unwound from said roller, and that as the carriage returns toward the main conveyer, they will be wound upon it. In this way, 10 the tapes 92 support the sheet during the advance of the carriage and then are removed from beneath the sheet as the carriage recedes, thereby leaving the sheet free to drop or settle upon the piling table 30. 15 It will be noted that as the tapes 92 withdraw their support from the sheet 110, they do so without exerting any pull or drag upon the sheet. This is an important and distinguishing feature of my invention. 20 In order to reciprocate the carriage 28, I provide two delivery connecting rods 122 which are connected at one end to the carriage and at the other end to delivery arms 123 which are keyed to a transverse shaft 124 having bearings in the delivery frame extensions 53. One of the connecting rods 122 is connected to the carriage frame 78 and the other is similarly connected to the carriage frame 79. In providing for this 25 connection, a pin 125 is secured to the forward end of the rod 122 and extends laterally therefrom into a bearing 126 formed upon the upper portion of the carriage frame and having a longitudinal slot 127 through which the pin may be moved into 30 its final position. A cotter pin 128 or other suitable means may be employed for holding the pin 125 within the bearing 126. To prevent undue shifting, the pin 125 is provided with a collar 129 which engages one 35 end of the bearing 126. With this construction the connecting rod may be readily removed from its bearing by simply withdrawing the cotter pin 128 and then with- 40 drawing pin 125 upward through the slot 127 of the bearing 126. The pin 125 ex- 45 tends far enough beyond the collar 129 so as to rest upon the upper edge of the adjacent way-bar 31 when it has been removed 50 from the bearing 126 in the manner just described and when the carriage has been moved out of the way.

At this point it may be mentioned that when the carriage 28 is to be removed from 55 the way-bars 31 for the purpose of operating the fly delivery, it is only necessary to remove the pins 125 from their bearings in the way just described and, in addition, to loosen the set-screws 95 in the ends of the 60 bar 93, to which the tapes 92 are secured, and lift the bar 93 from its pins 94 and allow the spring roller 83 to wind up the tapes and draw the bar 93 into the vicinity of the roller 83. When these steps have

been taken and the tapes have been thus 65 wound up upon the roller, the carriage 28 may be readily removed from the way-bars 31 and the space left free for the operation of the fly fingers 25 in the manner previously 70 described.

The delivery arms 123 are arranged to be oscillated back and forth by means of a crank arm 130 secured to the shaft 124 and arranged to be connected at its free end to one end of a connecting rod 131 which is connected at its other end to a crank arm 132 upon shaft 67. As the latter shaft is rotated, the connecting rod 131 is reciprocated with a corresponding reciprocation of the arms 123, the connecting rods 122 and 75 the carriage 28. When the carriage is to be removed and the reciprocating delivery mechanism replaced by the fly delivery mechanism, then the connecting rod 131 is disconnected from the crank arm 130. For 80 this purpose the crank arm 130 is provided with a laterally projecting pin 133 which is adapted to be engaged by a hook 134 upon the adjacent end of the connecting rod 131. When the connecting rod 131 is out of engagement with the crank arm 130, it preferably rests upon a pin 135 which projects 85 from the adjacent portion of the main frame 22.

The piling table 30 may be of any preferred construction, but it is narrow enough so as to pass freely between the way-bars 31 when it is raised to its elevated position, as shown in full lines in Fig. 1. As there shown, it is pivoted at its inner end to the delivery projections 53 and it is normally supported in the position shown in dotted lines in Fig. 1, by means of one or more adjustable legs 135 which rest upon a portion of the ink fountain 136. The table 30 is 100 also provided with props or legs 137 which are positioned so as to rest upon strips 88 on the way-bars 31 when the table is elevated. Suitable side and end boards 138 and 139 may be provided for guiding the 105 sheet as it settles into its final position upon the table after the tapes 92 of the carriage mechanism have been withdrawn or as it is brought into such position by the fly fingers 25. 115

In order that the parts may be raised into the position of Fig. 1, the strips 88 upon the way-bars 31 are cut away at one point, as shown in Fig. 11, so as to allow the anti-friction rollers 87 upon the carriage 28 to be drawn upward into the position shown in Fig. 1. In addition to this cutting away of strips 88, provision is made for attaching or connecting the free end of the main conveyer 24 to the upper ends of the delivery arms 123. In this way, the latter arms serve as props or supports for the conveyer 24. As shown at 140, the upper end of the arms

123 are hollowed out so as to provide seats for a pin 141 and 141^a upon the plates 40 of the conveyer frame. As clearly shown in Fig. 10, these pins 141 and 141^a are arranged to be reciprocated in bearings 142 formed in these plates. The inner end of the pin 141^a is connected by an arm 143 to a reciprocating rod 144 also bearing in the plates 40 and adapted to be shifted longitudinally back and forth. By reason of this connection, the pin 141^a moves back and forth with the rod 144. The pin 141 is connected at its inner end to one end of a lever 145 which is provided with a handle 146 and is pivoted 15 at an intermediate point to a bracket 147 carried by the associated plate 40. This lever is also connected on the side of the fulcrum adjacent to the handle 146 to the reciprocating rod 144. With this construction 20 it will be seen that the movement of the lever to the right of the position illustrated in Fig. 10, will force the pins 141 and 141^a outward into the path of movement of the delivery arms 123 and thereby bring them 25 into position to be seated in the seats formed at the upper ends of these arms. A spring pin 148 passing through a portion of the bracket 147 is adapted to engage holes 149 in the adjacent pin 141. These holes are two 30 in number and positioned so that when the pin 148 is in one of them, the pins 141 and 141^a will be in their extended position, and when pin 148 is in the other hole, the pins 141 and 141^a will be in retracted position, 35 that is to say, the position illustrated in Fig. 10.

When the parts are elevated and held so, the various mechanisms upon the press directly beneath the delivery mechanisms and 40 the piling table, may be quite readily inspected. This inspection will include the inspection of the form inking and distributing rollers 150 and the plate inking and distributing rollers 151 which coöperate with 45 the ink plate 152 and the form upon the bed 153. The mechanism for reciprocating the latter is not herein disclosed as the same constitutes no part of the present invention, but I preferably employ the reciprocating 50 mechanism illustrated and described in my United States Patent No. 1,063,273, granted June 3rd, 1913.

At this point it may be pointed out that the fly delivery shaft 29 is provided upon 55 the end distant from the actuating rack 62 with a crank arm 154 which is securely clamped to the end of the shaft by suitable clamping means, such as a bolt 155. At the outer end of the crank arm 154 is a pivot 60 156 upon which is journaled a bearing 157 which is secured to a vertical rod 158 which extends some distance below, through an opening in a fixed portion of the frame 159. A spring 160 surrounds the rod 158 and en-

gages the bearing 157 at one end and the 65 frame member 159 at the other. As the shaft 29 is reciprocated, the spring 160 is oscillated. The spring 160 acts as a cushion and comes into play in such capacity as the 70 fly sticks arrive near the end of their 180 degree sweep in each direction. This cushioning of the fly sticks by means of the spring 160 is of great importance on high speeds as it prevents the sticks from jumping. 75

The construction of the tape-holding bar 75 93 and spring roller 83 is similar. Each is composed of a hollow pipe. In the case of the bar, 93, this pipe is closed at each end by a plug or block 161, which is provided with a vertical opening 162 for the pin 94, 80 and a transverse threaded opening 163 for the set-screw 95. In the case of the roller 83, each end of the pipe is closed with a plug 164 which is provided with a central opening 165. These openings fit shaft 82 85 of the carriage 28. The bar 93 is furthermore provided with a saw-cut 166 which extends throughout its length and communicates with an enlarged opening 167. Any 90 number of such openings 167 may be provided, but I preferably employ one at each end of the bar, one being clearly illustrated in Fig. 13. In the case of roller 83, a similar saw-cut 168 communicates with a similar opening 169. In this case I also prefer- 95 ably employ an opening 169 near each end of the roller, although a larger number may be employed if desired. The tapes 92 are thickened at their ends so that they will not 100 pass through the saw-cuts 166 or 168. The tapes are preferably thickened by sewing the end around a piece of cord 170, although this end may be attained otherwise. The 105 openings 167 and 169 are made large enough to allow the thickened end of the tape to be passed through the opening and then moved lengthwise of the roller so as to bring the tape into the associated slot. When in this position the tapes are securely 110 held from withdrawal and they will be wound on and off the roller as before explained, without becoming in any way detached from the roller 83 or the bar 93. By this arrangement the tapes may be 115 readily shifted in the slots 166 and 168 to accommodate themselves to sheets of varying widths, or they may be readily withdrawn for the purpose of being replaced by new tapes, or for the purpose of replacing bar 93 or roller 83, as may be desired. 120

From the description heretofore given, it will be apparent that either type of delivery may be employed upon the press. In case the fly delivery is employed, the carriage 28 and the associated supporting tapes 92 125 are removed, while the delivery connecting rods 122 are left with their pins 125 resting upon the way-bars 31. At this time the ac-

truating rod 131 is idle and resting upon the pin 135. On the other hand, when the reciprocating or face-up delivery mechanism is being operated, the latch 74 is employed 5 to hold the arm 64 out of engagement with the cam 66 and operation of the fly delivery mechanism is therefore prevented.

In carrying out my invention it will be apparent that many alterations and modifications 10 may be made in the structure disclosed without departing from the spirit and scope of the invention. I therefore do not wish to be limited to the specific structure illustrated and described, but aim to 15 cover all such alterations and modifications by the terms of the appended claims.

What I claim as new and desire to secure by Letters Patent of the United States is:

1. In a printing press, the combination of 20 a main frame, an impression cylinder, a conveyer having its frame pivotally supported adjacent to said cylinder, a reciprocating carriage, pivoted carriage-actuating arms, connections between said arms and 25 said carriage, and means for connecting the free ends of said arms with the free end of said conveyer frame to hold the conveyer elevated to permit access to the parts of the press below it.

30 2. In a printing press, the combination of a main frame, an impression cylinder, a conveyer having its frame pivotally supported at a point adjacent to said cylinder, carriage way-bars extending from the free end 35 of said conveyer frame when in its conveying position, a carriage on said way-bars, arms pivoted to said main frame adjacent to the free end of said conveyer frame, connecting bars between said arms and said 40 carriage, means for oscillating said arms to reciprocate said carriage, and means for connecting the free ends of said arms with the free end of said conveyer frame to hold the latter elevated to permit access to the parts 45 of the press beneath it.

3. In a printing press, the combination of 50 a main frame, an impression cylinder, a conveyer having its frame pivotally supported adjacent to said cylinder, a reciprocating carriage, pivoted carriage-actuating arms, connections between said arms and said carriage, said arms being positioned to move in 55 their normal operation past the sides of said conveyer frame, laterally movable pins journaled in the sides of said conveyer frame adjacent to its free end, means for throwing said pins outward into the path of travel of said arms, and means on the outer ends of said arms for engaging said pins to enable 60 said arms to hold said conveyer frame in elevated position.

4. In a printing press, the combination of 65 a main frame, an impression cylinder, a conveyer having its frame pivotally supported

adjacent to said cylinder, a reciprocating carriage, pivoted carriage-actuating arms, connections between said arms and said carriage, said arms being positioned to move in their normal operation past the sides of said conveyer frame, laterally movable pins journaled in the sides of said conveyer frame adjacent to its free end, a pivoted lever having one arm secured to one of said pins, and a member secured to the other arm of said lever and to said other pin, whereby the actuation of said lever throws said pins outward into the path of travel of said arms. 70

5. In a printing press, the combination of 75 a main frame, an impression cylinder, a conveyer having its frame pivotally supported adjacent to said cylinder, a reciprocating carriage, pivoted carriage-actuating arms, connections between said arms and said carriage, said arms being positioned to move in their normal operation past the 80 sides of said conveyer frame, laterally movable pins journaled in the sides of said conveyer frame adjacent to its free end, a pivoted lever having one arm secured to one of said pins, a member secured to the other arm, 85 of said lever and to said other pin, whereby the actuation of said lever throws said pins outward into the path of travel of said arms, and means for holding said pins in either 90 extended or retracted position. 95

6. A printing press delivery mechanism comprising way-bars, a carriage movable thereon, two shafts on said carriage, connections between said shafts whereby the rotation of one shaft in one direction rotates the other shaft in the opposite direction, coöperating gripper fingers mounted on said shafts and movable toward each other to engage the sheet upon one movement of said shafts and away from each other upon the other movement of said shafts, a spring-actuated toggle connected with one of said shafts and operative to give them their different movements when thrown into its different positions, and coöperating means upon said carriage and one of said ways for throwing said toggle into its different positions at different points in the travel of said carriage. 100 105 110

7. A printing press delivery mechanism 115 comprising coöperating gripper fingers for engaging the sheet, two shafts on which said fingers are mounted, connections between said shafts whereby the rotation of one shaft in one direction causes a rotation of the other shaft in the opposite direction, a spring-actuated toggle connected to one of said shafts and operative when thrown into its different positions to rotate said shaft in opposite directions with a corresponding 120 movement of the coöperating fingers on said shafts toward each other to grip the sheet and from each other to release it, and means 125

for throwing said toggle into its different positions.

8. A printing press delivery mechanism comprising main conveying tapes, fly delivery fingers arranged to lie normally between said tapes and beneath the path of travel of the sheet thereon, a delivery table, a reciprocating delivery carriage movable above said table, connections for actuating said carriage readily separable therefrom, a spring roller and coöperating fabric lying below the plane of travel of the sheet and operative to support the sheet during its reciprocating delivery advance and to free it when advanced to a position above said table, means for securing said fabric so that it may be readily detached from the press and removed with said carriage to allow said fly delivery fingers to operate.

20. 9. A printing press delivery mechanism comprising a reciprocating carriage, way-bars on which said carriage travels, pivoted carriage-actuating arms movable in planes adjacent to said way-bars, connecting bars uniting the free ends of said arms to said carriage, bearings in said carriage adjacent to said way-bars, studs extending from said connecting bars into said bearings and far enough to rest upon the way-bars when said carriage is removed therefrom, and readily detachable means for securing said studs in said bearings.

10. A printing press delivery mechanism comprising a carriage, driving means for said carriage, a readily detachable connection between said driving means and carriage whereby the latter may be readily freed for removal from the press, a spring roller secured to the carriage beneath the path of travel of the sheet, a fabric secured to said roller, and a readily detachable connection between the free end of said fabric and a fixed part of the press whereby said fabric may be detached from the body of the press and upon being wound upon said spring roller be removed with said carriage.

11. A printing press delivery mechanism comprising a reciprocating carriage, a spring roller secured thereto beneath the path of travel of the sheet, fixed brackets having upwardly extending pins, a bar having apertures for fitting over said pins, and a fabric secured to said roller at one end and to said bar at its other end, whereby said bar may be readily removed from said pins and removed with said carriage from the press.

12. A printing press delivery mechanism comprising coöperating gripper fingers for engaging the sheet, connections between said fingers whereby the rotation of one finger in one direction causes a rotation of the other finger in the opposite direction, a spring-actuated toggle associated with said

connections and operative when thrown into its different positions to actuate said connections to cause a movement of said fingers in opposite directions on the one hand to grip the sheet and on the other to release the sheet, and means for throwing said toggle into its different positions.

13. A printing press delivery mechanism comprising main conveying tapes, a reciprocating carriage, a tape support located near the delivery ends of said main conveying tapes beneath the path of travel of the sheet, a second coöperating tape support located upon said carriage, one of said tape supports being in the form of a spring roller, additional tapes extending between said supports and adapted to be wound up as the carriage retreats and unwound as the carriage advances, and fly-delivery fingers arranged to lie between said main conveying tapes and having their hubs located between the delivery ends of said main conveying tapes and the receiving ends of said additional tapes and just below the path of travel of the sheet so as to support the sheet as it passes from one set of tapes to the other.

14. A printing press delivery mechanism comprising main conveying tapes, additional tapes for receiving the sheet as it passes from said main tapes, and fly-delivery fingers arranged to lie between said main conveying tapes and having their hubs located between the delivery ends of said main tapes and the receiving ends of said additional tapes just below the path of travel of the sheet so as to support the latter as it passes from one set of tapes to the other.

15. A printing press delivery mechanism comprising reciprocating gripper fingers for gripping the forward edge of the sheet and carrying it forward, spring actuated toggle mechanism for opening and closing said fingers, and a catch for tripping said toggle to open said fingers at the beginning of the return stroke of said fingers.

16. A printing press delivery mechanism comprising a reciprocating carriage, a spring roller secured thereto beneath the path of travel of the sheet, a fixed support, tapes secured at their ends to said spring roller and support respectively and adapted to wind on and off said roller as said carriage reciprocates, fingers lying between said tapes adjacent to said spring roller, and means for holding the ends of said fingers above the plane of the tapes as the latter are being wound up and against the roller as the tapes are being unwound therefrom.

17. A printing press delivery mechanism comprising a conveyer having its frame pivotally supported at one end, fly-delivery fingers pivotally supported at a point adjacent

to the free end of said conveyer when in operating position, said fingers being adapted to lie between the tapes of said conveyer and below the plane of travel of the sheet, a reciprocating rack and a coöperating toothed gear segment for actuating said fly-delivery fingers, a shaft for said fingers, an arm on said shaft adjacent to said segment,

and a spring-pressed pin for securing said arm and segment together, said pin being carried by the one and coöperating with a hole in the other.

In testimony whereof I have hereunto subscribed my name this 7th day of January, A. D. 1916.

CYRUS A. McCAIN.
